Primary Examiner—Janice E. Seeger
Attorney, Agent, or Firm—Howell & Haferkamp, L.C.[57] **CLAIM**

The ornamental design for a panel headboard, as shown and described.

DESCRIPTION

FIG. 1 is a front view of a panel headboard showing our new design, it being understood that the back is plain and does not form a part of the claimed design;

FIG. 2 is a right side view thereof, it being understood that the opposite side is the mirror image of the side shown; and, FIG. 3 is a top view thereof, it being understood that the bottom side is plain and does not form a part of the claimed design.
